UNITED STATES PATENT OFFICE.

MAURICE LACHMAN, OF NEW YORK, N. Y., ASSIGNOR TO LACHMAN MANUFACTURING COMPANY, OF NEW YORK, N. Y., A CORPORATION OF DELAWARE.

PAPER CONTAINER.

1,138,120.

Specification of Letters Patent.

Patented May 4, 1915.

Application filed April 12, 1913. Serial No. 760,596.

To all whom it may concern:

Be it known that I, MAURICE LACHMAN, a citizen of the United States, and a resident of New York, in the county of New York and State of New York, have invented 5 certain new and useful Improvements in Paper Containers, of which the following is a specification.

This invention relates to non-metallic 10 shipping and storing containers or receptacles and particularly to such types as comprise a body formed of paper or other similar material.

The invention particularly relates to the 15 manner of reinforcing the paper body and securing the heads or closures thereto.

The object of the invention is to provide 20 metallic reinforcing means for the paper body and to secure both the heads to the body by such metallic reinforcement whereby a rigid, strong container, adapted to resist hard usage, is attained.

A further specific object is to avoid any 25 waste of material in the construction of the reinforcement or head securing means and thereby cheapen the cost of manufacture.

To these ends the invention consists in 30 the improved structure of non-metallic container hereinafter more particularly described and then specified in the claims.

In the accompanying drawings, Figure 1 35 is a side elevation and partial section of a container constructed in accordance with this invention in one of its forms. Fig. 2 is an enlarged partial section of the same 40 showing the head securing means. Fig. 3 is a plan of the part shown in Fig. 2. Fig. 4 is a cross-section through a modified form of reinforcing and head securing member. Fig. 5 is a plan view of a further modification in the form of said member.

Without in any manner limiting the invention thereto, it will be herein shown and described as applied to a keg or barrel and 45 when used with such forms, the body consists preferably of a cylinder of paper, straw-board or other similar non-metallic material 1 formed in any desired manner. The cylinder 1 is preferably formed of a 50 number of layers of paper superimposed on each other, preferably by spinning, and compressed into a very solid mass, the various layers being preferably united by a suitable cement, glue or other adhesive whereby 55 a very rigid wall is attained. The specific

manner of forming the cylinder or body forms no part of my invention and further description will be dispensed with.

2 indicates a band or hoop preferably located on the outside of the cylinder 1, one 60 being disposed at each end of the cylinder and each is preferably provided with a lateral flange 3 resting on the edge of the cylinder to protect such edges from mutilation.

The heads or closures for the cylindrical 65 body 1, one being provided for each end, may be of any suitable construction, a preferred one comprising a paper disk 4 the edges of which are secured between inwardly projecting flanges 5, 6 of an annular 70 metal rim. The rim is also preferably provided with an outwardly projecting flange 7 which seats on the edges of the cylinder 1 or on the flange 3 when such flange is employed. If desired additional means such 75 as the wire 8 may be employed to staple the disk 4 in the rim and which wires also serve as a reinforcement for the head. The construction of the head forming no part of the present invention, further description will 80 be dispensed with.

9 indicates a metallic band preferably of sheet metal passing around preferably on the outside of the cylinder 1 at about the middle, the ends being joined together in 85 any suitable or desired manner. The band 9 is provided with a plurality of spaced apart metal strips 10 secured to said band and emanating therefrom preferably perpendicular thereto. A set of said strips 90 emanate from the upper and lower edges of the band toward each end of the cylinder and are of such length that their free ends 11 project beyond the cylinder ends as indicated in Fig. 1. Preferably the band 9 95 and strips 10 are stamped from one piece of sheet metal, the spaces between the strips also being preferably equal in width to the width of the strips whereby no metal is wasted in the formation of this member, the 100 metal removed from the spaces representing the strips of another set of reinforcing strips 10. The strips 10 emanating from each edge of the band 9 are preferably in line but they may be alternately disposed or 105 staggered if desired. The band 9 and its attendant strips 10 may be located on either the inside or the outside of the cylinder 1, the free ends 11 of the strips being bent over the annular metal rim of the heads 4 110

- to secure the heads to the body. Thus a rigid metallic reinforcement for the body is provided which at the same time provides the means for effectually securing both 5 heads to the body and bracing the same. If desired to give further rigidity, all or some of the strips 10 may be secured to the bands or hoops 2 in any manner as by passing the ends through eyes 12 formed in the hoops 2.
- 10 Instead of the strips 10 being integral with the band 9 as shown in Fig. 1, they may be separate pieces secured to the band by any other suitable means, another method being shown in Fig. 4 as an instance. In 15 this modification, the strips are alternately disposed and the ends turn over the edge of the band 9 as indicated at 13, the strips being disposed between the inner periphery of the band and the periphery of the cylinder 1.
- 20 While in both of the forms above described the band 9 is merely a single length of metal from which both sets of strips 10 emanate, the said band may comprise two 25 separate lengths or bands 9, 9' as shown in Fig. 5, the bands 9 and 9' being united to each other by connectors 14 at intervals about the circumference. Said connectors may be riveted, welded or otherwise secured 30 to the bands. In this modification each separate band 9, 9', constituting with the connectors 14 the band of the reinforcement, is provided with its own set of head securing strips 10.
- 35 It will be understood that various modifications of the present invention may be resorted to without departing from the spirit thereof as set forth in the appended claims, it being understood that the invention is not 40 limited to the forms shown which are for the purpose of illustration only.
- What I claim as my invention is:—
1. A container including in combination, a body of paper-like material, a metallic 45 band secured to said body, metallic straps emanating from said band, hoops adjacent the ends of said body, loops on said hoops and extending over said straps, holding devices formed on said straps, and a head seated on said paper-like body and secured 50 in position by the holding devices on said straps.
2. A container including in combination, a cylindrical paper body, a metallic band encircling said body, flat metallic members 55 secured to said band and having a greater total length than the length of the body, hoops adjacent the ends of said body and having portions extending over the ends of said flat metallic members, heads seated in 60 the ends of said body, and hooks formed in the ends of said members and extending over the edge of the rims at the ends of said body and coöperating with said heads to secure said heads to said body. 65
3. In a container in combination, an integral cylindrical body of fibrous material, metallic hoops on each end of said cylindrical body, loops formed upon said hoops, stay members having a total length greater 70 than the length of said body extending lengthwise of said body and through said loops, a head seated in one end of said body, and hooks formed upon said stays and co-operating with said head to secure said head 75 in position.
4. A container comprising an integral body of fibrous material, a supporting member coöperating with said integral body, said supporting member comprising a hoop 80 and flat strips extending from said hoop, a head seated in one end of said body, a hoop adjacent the end of the body in which the head is seated, means to secure said strips to said last mentioned hoop, and means carried 85 by said strips to secure said head within the end of said body.
- Signed at New York, in the county of New York and State of New York, this 10th day of April, A. D. 1913.
- MAURICE LACHMAN.
